CLAIM

I claim the ornamental design for box, as shown and described.

DESCRIPTION

FIG. 1 is a top, front, right side perspective view of a box embodying my new design;

FIG. 2 is a bottom, rear, right side perspective view thereof, the left side view being a mirror image of the right side;

FIG. 3 is a plan view thereof in an unfolded condition; and,

FIG. 4 is a perspective view following removal of the pull

tab with the box shown partially folded.

The broken line showing of files inside the box is for illustrative purpose only and forms no part of the claimed design.
